TOP SPINNER AND LAUNCHER

Roy Francis Bourelle and Beatrice Thresea Widdoes, Creston, British Columbia, Canada

Application February 24, 1950, Serial No. 145,964

4 Claims. (Cl. 46—72)

1

This invention relates to improvements in toys for mechanically spinning and launching tops, and the object of the invention is to manually couple the top to the motor which spins it; mechanically hold the top while being spun, and then manually uncouple the top from the spinner for launching down an inclined plane.

Broadly considered the device comprises a suitable frame adapted to carry a motor to spin the top, and to rest upon a table or the floor onto which the spinning top is to be launched; a two-part launching means hinged to said frame, and means carried by said frame to support said launching means and to permit displacement thereof to allow the top to be manually coupled to and uncoupled from the motor and launched, as hereinafter more particularly explained.

Figure 1, is a side elevation of the toy, showing a top mounted to be spun by the motor before launching.

Figure 2, is a side elevation of the means for manually raising and lowering the launching means, showing the same supported by part of the frame.

Figure 3, is a section on the line 3—3, Figure 1.

Figure 4, is a detail showing the means for coupling the top to the motor.

Figure 5, is a side elevation of the launching plate, and Figure 6, is a plan view of part thereof.

Figure 7, is a plan view of part of the launching plane.

In the drawings, like characters of reference refer to the same parts.

As shown the frame to support the top and the launching means, and the motor, consists of a vertical post 2, suitably fastened to a horizontal base 3. The motor 4, is suitably mounted on the post 2, and the electric circuit therefor is controlled by any suitable switch 5.

By means of the side walls 6, the post 2, and base 3, are securely braced together, and supports provided for the means to vertically move the launching plate and the inclined launching plane down which the spinning top slides. The launching plate 7, is pivoted by a pin 8, in the walls 6, with its free end overlapping the upper end of the inclined plane 9, which is hinged at its lower end to the outer end of the base 3. The upper end of the plane 9, at times moves between the walls 6, and it is centrally longitudinally provided with a groove or channel 10, which is in alignment with the shallow depression 11, formed centrally longitudinally in the launching plane 7.

Any suitable means may be used to provide for

the raising and lowering of the outer end of the plate 7, and the upper end of the plane 9. The preferred means for this purpose comprises a crank 12, journalled at 13, in the walls 6. This crank is provided with a handle 14, at one end and at the other end with a friction rod 15, which has close contact with an arcuate rack-provided plate 16, carried by one of the walls 6. Contact between the rod 15, and the plate 16, will maintain the crank 12, in the desired position. This crank is the support for the upper end of the plane 9, and the outer end of the plate 7.

To couple the top 17, to the shaft 18, of the motor, the crank 12, is moved in the direction of arrow (Figure 2) thus permitting the overlapping ends of the plate 7 and plane 9, to be lowered by gravity far enough to permit the pin 19, in the socket 30, in the top of the top to be inserted in the slot 20, in the end of the shaft 18. While

the top is manually held in this position, the crank 12, is returned to normal position shown in Figure 1, to lift up the plate 7, and the plane 9, and thus seat the pin 21, of the top in the shallow depression 11, formed in the outer end of said plate. The switch 5, is now closed and the motor spins the top. When the crank 12, is moved again in the direction of arrow far enough the overlapping ends of the plate 7, and plane 9, will be moved down by the weight of the top until the top is disengaged from the motor. When this occurs the top will slide down the now inclined plate 7, onto the plane 9, which launches it onto the table or the floor.

Since the plate 7, is normally held in a horizontal position the axis of the top is held in alignment with the axis of the shaft of the motor with the pin 21, in the shallow depression 11, and hence there will be no lateral displacement of the top while being mechanically spun.

With a little practice, several tops may be spinning on the table or floor simultaneously. A number of musical tops because of the varying rates of rotation thereof will often produce very pleasing harmonious musical sounds. The shaft of the motor is shown provided with a pulley 22. This pulley is not essential. But if the toy be placed on its side, a belt (not shown) may be passed around this pulley to drive various types of toys.

Various changes in construction will at once suggest themselves to one skilled in the art without going outside the scope of this disclosure nor of the claims forming part thereof.

We claim:

1. A mechanical top spinner and launcher

comprising a suitable frame; a normally horizontal launching plate hinged at its inner end on said frame; a longitudinally centrally-grooved inclined plane, hinged at its outer end to said frame while its upper end carries the outer end of said plate, the longitudinal groove in said plane lying in alignment with a shallow depression in said plate, and manual means carried by said frame whereby the overlapping ends of said plate and plane may be raised and lowered.

2. A mechanical top spinner and launcher comprising a suitable frame; a normally horizontal launching plate hinged at its inner end on said frame; a longitudinally centrally-grooved inclined plane, hinged at its outer end to said frame while its upper end carries the outer end of said plate, the longitudinal groove in said plane lying in alignment with a shallow depression in said plate; a crank journaled in said frame below the overlapping ends of said plate and plane, and adapted to contact said plane to support the said inner ends and to be manually moved so that said inner ends may be raised and lowered.

3. The combination as set forth in claim 2, characterized in that friction means is provided to maintain said crank in adjusted positions.

4. A mechanical top spinner and launcher

comprising a suitable frame; a normally horizontal launching plate hinged at its inner end on said frame; a longitudinally centrally-grooved inclined plane, hinged at its outer end to said frame while its upper end carries the outer end of said plate, the longitudinal groove in said plane lying in alignment with a shallow depression in said plate; an electric motor supported by said frame, provided with a slot in the lower end of its shaft; a top; a pin in a socket in the top of said top adapted to be placed in the said slot to couple the top to the motor, and manual means carried by said frame whereby the overlapping ends of said plate and plane may be raised and lowered.
